G. M. TODD

AUTOMATIC LIGHTER FOR STOVES

Filed March 30, 1927

INVENTOR

GEORGE M. TODD

BY

Richard J. Cook
ATTORNEY

UNITED STATES PATENT OFFICE.

GEORGE M. TODD, OF SNOQUALMIE, WASHINGTON.

AUTOMATIC LIGHTER FOR STOVES.

Application filed March 30, 1927. Serial No. 179,562.

This invention relates to improvements in fire lighting devices, and particularly to a device adapted for lighting a fire in a stove. It is the principal object of this invention to provide a fire lighting device that is designed particularly for use with a kitchen range or stove and which embodies means for holding matches and other means whereby the matches may be struck and lighted and then extended into the position for lighting the fire. A further object of the invention resides in the provision of a device as above stated which may be released by a connection with an alarm clock, or the like, so that a fire may be started at any desired time for which the clock may be set.

Other objects of the invention reside in the various details of construction and combination of parts as is hereinafter described. In accomplishing these and other objects of the invention, I have provided the improved details of construction, the preferred forms of which are illustrated in the accompanying drawings, wherein—

Figure 1 is a perspective view of a fire lighting device embodied by this invention, showing it in set position.

Figure 2 is a top view of the same.

Figure 3 is a side elevation, illustrating the manner of attaching the device to a stove and showing the parts in the position they assume after being released by the clock.

Figure 4 is a transverse, sectional detail taken on the line 4—4 in Figure 2.

Figure 5 is a perspective view of the end portion of the match carrying plunger.

Referring more in detail to the drawings—

1 designates what may be a flat metal plate forming the base of the device. This is disposed horizontally in order that it may serve as a support on which an alarm clock, or the like, as designated at 2 in Figure 3, may be supported and it is provided, at one edge, with two laterally extending prongs 3 and 4 adapted to project within the draft openings 5 in the side of the stove and to hook over the lower edges of these openings as a means of supporting the base plate horizontally and closely adjacent the side wall 6 of the stove. One of these prongs is adjustably attached to the plate so that it may be adjusted to openings that are spaced at various distances apart. A brace 7 is also attached to the base 1 for engaging the side wall of the stove to

supplement the prongs 3 and 4 in supporting the base.

Fixed along one edge of the base 1 is a straight, horizontally extending tube 8 that extends beyond the base and through one of the draft openings 5, with its inner end terminating at a point directly beneath the grate of the stove in which the fuel for a fire is laid. This tube is fixed to the base by means of an encircling clip 9, as shown in Figure 2.

Slidably contained in the outer end of the tube is a plunger 10 that is provided at its inner end with sockets 11 in which matches, as shown at 12 in Figure 2, may be held and, at its outer end, has a clip 13 fixed thereto. Coiled springs 14 are attached to this clip and to laterally extending ears 15 formed on the clip 9, for the purpose of drawing the plunger through the tube.

Formed in the tube 8, just forwardly of the clip 9, is a transverse slot 18 through which one end of an elongated match striking plate 19 is projected. This plate has one face roughened, as shown at 20 in Figure 4, and against this roughened face the heads of matches held by the plunger may rest and, at its outer end, it is attached to one end of a coiled spring 22. The spring 22 is connected, at its outer end, to an upstanding ear 23 at the edge of the plate 1 and is held under tension so as to pull the plate outwardly from the slot when it is released.

When the parts are in set position, the plate 19 is held in the slot of the tube by means of a stop 24 that is turned up from the base in position to engage with an opposingly facing shoulder 25 that is formed in the lower edge of the plate, and, in order to release the shoulder from the stop so that the spring may pull the plate from the tube, I have provided a trigger, or release bar, 26 which extends beneath the plate closely adjacent the shoulder and is pivotally attached at one end to the base, as at 27, and at its other end is adapted to be connected by means of a cord 28 to the winding stem 29 of an alarm clock, or the like, as indicated at 2.

In using the device the tube 8 is projected through one of the draft openings of the stove so that its inner end is disposed closely adjacent the under side of the grate on which the fuel to be lighted is placed. The prongs 3 and 4 are hooked over the lower

edges of the draft openings and the brace bar seated against the side wall of the stove so that the base plate will be held in horizontal position; the plunger 10 is then withdrawn and the matches 12 are mounted in the sockets of its inner end. The match striking plate 19 is then projected through the slot 18 of the tube 8 and its shoulder is seated against the stop so that it will be held against the tension of the spring 22. The plunger is then projected into the tube so that the heads of the matches engage with the plate thereby holding the plunger in extended position, as shown in Figure 2, 10 against the tension of the spring 14. The clock 2, which is used to release the device, after being set to operate the alarm mechanism at a certain predetermined time, is then placed on the base plate 1 and the cord 20 28 is attached to the outer end of the trigger member and to the alarm winding stem of the clock. At the predetermined time at which the alarm is set, the cord 28 will be drawn in by winding of the stem 29 of the 25 clock and this will pull upwardly on the trigger to thereby unseat the shoulder of the striking plate from the stop which holds it and the spring 22 will draw the plate quickly from the tube. The frictional contact of the roughened surface of the plate drawn quickly across the heads of the matches causes them to be lighted and removal of the plate from the tube permits the plunger to be drawn inwardly by the 30 tension of the springs 14 so that the matches will be projected from the inner end of the tube 4 in position for lighting the fire, the inward movement of the plunger being limited by the restricted inner end portion of 40 the tube.

Such devices may be made in various shapes, sizes in accordance with the use to which they are to be put and it is readily apparent that various details of construction 45 may be altered to meet the requirements without departing from the spirit of the invention.

Having thus described my invention, what I claim as new therein and desire to secure 50 by Letters-Patent, is:

1. A device of the character described comprising a support, a tube on the support, a match holder movable in the tube, a match striker in the tube adapted to be engaged by matches in the holder and whereby said matches will be struck incidental to its withdrawal from the tube, means for normally retaining the striker in the tube, means for releasing it from the said retaining means 55 and means for actuating the match holder as the striker is removed from the tube to cause the matches to be projected from the tube.

2. A device of the character described comprising a supporting plate, a tube on the plate, match holding means slidable in the tube, a match striking plate removably disposed in the tube and adapted to be engaged by matches held in the holding means and whereby said matches will be struck by withdrawal of the plate, means operable by withdrawal of the plate for actuating the match holding means within the tube to cause the struck matches to be extended from the end of the tube, means normally holding the plate in the tube and means for releasing the plate from its holding means. 65 70 75

3. A device of the character described comprising a supporting plate, a tube fixed on the plate, a match striking plate extended through the tube and having a shoulder 80 thereon, a stop on the base adapted to be engaged by the shoulder, a spring attached to the striking plate and to the base whereby the striking plate will be removed from the tube when the shoulder thereon is released from the stop, a match holding plunger 85 slidable in the tube and whereby matches will be held against the striking plate, a trigger movable to release the striking plate from the stop and a spring attached to the 90 plunger whereby the latter will be actuated when the striking plate is removed to cause the struck matches to be projected from the end of the tube.

4. A device of the character described 95 comprising a supporting plate for a clock or the like, means for attaching the plate to a stove, a tube mounted on the plate and adapted for extension within the stove and having an open inner end, a match striking 100 plate extended through the tube and having a roughened surface and having a shoulder, a stop on the base plate adapted to engage the shoulder to retain the plate within the tube, a spring attached to the base and to 105 the striking plate for removing the latter from the tube when the shoulder is released from the stop, a plunger slidably contained in the tube provided with match holding means at its inner end whereby the matches will be held in contact with the roughened surface of the striking plate and whereby they will be struck by withdrawal of the plate from the tube, a trigger adapted for connection with a clock supported on the 110 base for releasing the striking plate from its stop and a spring attached to the plunger whereby the struck matches will be projected from the end of the tube when the striking plate is removed. 115 120

Signed at Seattle, Washington this 21st day of February 1927.

GEORGE M. TODD.
